UNITED STATES PATENT OFFICE.

JACOB J. BUSENBERG, OF ROCK ISLAND, ILLINOIS.

CAR JOURNAL-BOX.

SPECIFICATION forming part of Letters Patent No. 503,405, dated August 15, 1893.

Application filed November 8, 1892. Serial No. 451,287. (No model.)

To all whom it may concern:

Be it known that I, JACOB J. BUSENBERG, a citizen of the United States, residing at Rock Island, in the county of Rock Island and State 5 of Illinois, have invented a new and useful Dust-Guard Protector for Journal-Boxes, of which the following is a specification.

My invention relates to that class of journal boxes which are provided with dust guard 10 slots, and the object of my invention is to exclude dust from the journal box by lining or facing the inner surfaces of the front and rear walls of said slot so that the diaphragm will fit closely and snugly in said slot.

15 In dust guard slots, as now constructed in journal boxes, the inner surfaces of the walls are uneven and rough, and for this reason the diaphragm which is inserted in the slot does not fit closely so as to exclude dust, and as the apertures through such walls are required to be vertically elongated so that the box can be raised when the brass is removed, or a new one put in, consequently the diaphragm through which the journal passes is necessarily of less length 20 vertically than the depth of the slot. It has been found in practice that this old form of construction does not exclude the dust from the journal box and hence is objectionable, and especially when such box is also used as 25 an oil cell, because the dust mingling with the lubricant, seriously affects the journal and the brass, cutting them and wearing them out rapidly.

I accomplish the object of my invention by 30 the mechanism illustrated in the accompanying drawings, in which—

Figure 1 is a view of the longitudinal vertical section of the rear end of a journal box. Fig. 2 is a plan view of the form or shape of 35 the lining or facing used upon the inner surfaces of the front and rear walls of the dust guard slot. Fig. 3 is a plan view of the diaphragm and Fig. 4 is also a view of the longitudinal vertical section of the rear end of a 40 journal box, showing the method by which said linings and diaphragm are inserted in the slot.

Similar numerals of reference refer to similar parts throughout the several views.

In the drawings, 1 represents the journal box, 2 the dust guard slot, 3 the journal, 4 the 50 diaphragm and 5 the brass.

I use a facing or lining 6, preferably of felt, although any other suitable material may be used, and preferably this facing or lining is rectangular in form so as to conform to the 55 rear and front walls of the dust guard slot and provided with an aperture 7 of similar form and size as the aperture 8 through the walls of said slot. The facing or lining 6 is thoroughly oiled and the diaphragm is placed in suitable position so that a facing or lining is upon either side. Then I use two thin sheets of metal 60 represented in Fig. 4 by 9—9 which are placed on the outer sides of said lining or facing and the same are then placed in said slot, and when 65 in position the sheets of metal are withdrawn. The felt facing or lining being flexible fills the space between the walls of the dust guard slot and the diaphragm, so that dust will be excluded from entering the journal box. 70

From the description given, persons skilled in the art, will understand the method of construction and operation of my device.

In a pending application for Letters Patent, Serial No. 454,528, filed December 8, 1892, I 75 show and describe another mode of making and introducing the dust-guard at the rear of the journal-box; and I do not herein claim the method or structure therein set forth.

What I claim as new, and desire to secure 80 by Letters Patent, is—

In a journal box provided with a dust guard slot, and in combination with the diaphragm and linings, the metal plates 9—9 for the purpose of placing said diaphragm and linings 85 in position in said slot, substantially as described.

JACOB J. BUSENBERG.
